UNITED STATES PATENT OFFICE.

JOHN D. TOMPKINS, OF VALATIE, AND FREDERICK H. FULLER, OF POTSDAM, NEW YORK, ASSIGNEES TO TOMPKINS-HAWLEY-FULLER COMPANY, OF VALATIE, NEW YORK, A CORPORATION OF OREGON.

PROCESS AND APPARATUS FOR WATERMARKING PAPER.

1,196,181.

Specification of Letters Patent. Patented Aug. 29, 1916.

Application filed July 24, 1913. Serial No. 780,868.

To all whom it may concern:

Be it known that we, JOHN D. TOMPKINS and FREDERICK H. FULLER, of Valatie, in the county of Columbia, and in the State of New York, and Potsdam, county of St. Lawrence, and State of New York, respectively, have invented certain new and useful Improvements in Processes and Apparatus for Watermarking Paper, and do hereby declare that the following is a full, clear, and exact description thereof.

Our invention relates particularly to a process and apparatus for producing glazed water-marks in paper.

Hitherto paper has been water-marked by displacing the fibers in the paper in such a manner that light would be more readily transmitted by the portions of the web containing the displaced fibers than in the remainder of the web. The displacement of the fibers has, however, caused the portions of the web so treated to be much weakened and the result has been to weaken the web of paper as a whole. A web of paper so attenuated is not so valuable commercially as a web containing water-marks and not having the weakness of paper so treated. The web of paper should be such as to have equal tensile strength in all parts and in every direction.

In general our invention comprises the production of water-marks in paper by the application of heat and pressure. A web of paper so treated has very clearly defined water-marks and becomes glazed at the same time that the water-marks are produced in the paper.

While our invention is capable of being carried out in many different ways, we have described hereinafter one form of the process, and used in connection therewith certain forms of apparatus which we have shown in the accompanying drawings, in which:—

Figure 1 is a side elevation of a machine equipped with our invention, the same being shown somewhat diagrammatically; Fig. 2 is a cross-section of an embossing roll; Fig. 3 is a fragmentary view of the inside elevation of the same; and, Fig. 4 is a side elevation of an embossing band and supporting rolls therefor, which may be used to take the place of the embossing roll shown in the preceding figures.

In the drawings, reference being had to Figs. 1, 2, 3 and 4, 1 indicates a paper machine of any desired character in which there is shown a traveling web of paper 2 which passes between a pair of belts 3 which conduct the web of paper between a pair of pressure rollers 4. After leaving the pressure rollers 4, the web of paper is conducted over a heating drum 5 by the upper belt 3 which passes over a small press roll 4^a located over and adjacent to the heating drum 5. While on the heating drum, the web of paper passes beneath a roller 6 carried in the ends of a pair of arms 7 pivoted to any suitable support upon a pivot 8. An adjustable weight 9 may be placed in any one of a series of notches 10 in the top of one of the levers 7, in order to give the requisite pressure to the roll 6. At the extreme end of one of the arms 7 there is attached a chain 11 which passes over a roller 12 so that by operating the chain 11 the roller 6 may be moved into or out of contact with the web of paper 2 upon the heating drum 5. It will be understood that in this form of our invention the roller 6 carries upon its periphery, projections 13, as shown in Fig. 3, in order to produce water-marks of the desired shape in the web of paper while on the heating drum 5. The web of paper 2 passes around the heating drum 5 and comes into contact, at the lower side thereof, with a crimping plate 14 which is constructed in the usual manner. Thereafter, the crimped paper passes to a drier 15 made in any manner desired, and shown diagrammatically in Fig. 1 as a drying apparatus of the well-known type.

Instead of making use of a roller 6 having projections 13 to give the web of paper water-marks of the desired shape, we may make use of a smooth roller 16, as shown in Fig. 4, having a band of felt or other similar material 17, passing around the same and around a series of guide rolls 18. One of said guide rolls 18 may be upon the same axis as the roller 12. In order to give the web of paper water-marks of the desired shape, the band 17 has sewed thereto, or attached thereto in any other desired manner, a number of raised portions 19.

The operation of the process is as follows: The web of paper 2, after leaving the paper-making machine 1 in a somewhat moist

condition, passes over the heating drum 5, and while heated upon said drum is subjected to pressure from the roll 6 or the roll 16, the pressure of which may be adjusted by the movement of the weight 9. The pressure which the projections carried upon the roller 6 or 16 exert upon the body of the traveling web of paper results in producing water-marks having the shape of said projections, which water-marks are very clearly defined. At the same time, the paper is given a glazed surface so that the resulting product is a glazed, water-marked paper. It will be understood that in producing water-marks in this manner, the fibers of the web of paper are not displaced so that all portions of the web of paper contain the same amount of paper stock, and therefore have an equal strength throughout. The web of paper, after being water-marked in this manner, is crimped by the crimping plate 4 and is then conducted over the drier to entirely remove the remaining moisture in the paper.

25 While we have described our invention above in detail, we wish it to be understood that many changes may be made therein without departing from the spirit of our invention.

30 We claim:

1. The process which comprises making a paper web, then producing water-marks in the paper web while moist and before it has been dried by the application of pressure to the web on a drying surface, thereby causing the paper to adhere to said surface, and then crimping the entire web of paper while still adhering to the drying surface.
2. The process which comprises making a paper web, then producing water-marks in the paper web while moist and before it has been dried by the application of pressure and heat to the web on a drying surface, thereby causing the paper to adhere to said surface, and then crimping the entire web of paper while still adhering to the drying surface.
3. The process which comprises making a paper web, then producing glazed water-marks in the paper web while moist and before it has been dried by the application of pressure and heat to the web on a drying surface, thereby causing the paper to adhere to said surface, and then crimping the entire

web of paper while still adhering to the 55 drying surface.

4. The process which comprises making a paper web, pressing the same on to a drying surface, producing water-marks in the paper web while moist and before it has been dried, 60 by the application of additional pressure upon restricted areas in said web on the drying surface, thereby causing the paper to adhere to said surface, and then crimping the entire web of paper while still adhering 65 to the drying surface.

5. In a device of the character described, a device having a heated surface, water marking means for pressing on the same, comprising a surface having differences in its surface elevations, and a crimping device co-operating with the heated surface. 70

6. In a device of the character described, a device having a heated surface, means for pressing on the same, comprising a surface 75 having differences in its surface elevations, means for adjusting the pressure thereof, and a crimping device co-operating with the heated surface.

7. In a device of the character described, 80 a heated drum, a water marking pressure roll for pressing on the same, having differences in its surface elevations and a crimping device co-operating with the heated drum.

8. In a device of the character described, 85 a heated drum, a water-marking pressure roll for pressing on the same, having differences in its surface elevations, means for adjusting the pressure thereof and a crimping device co-operating with the heated drum. 90

9. In a device of the character described, a heated drum, a water marking pressure roll for pressing on the same, having differences in its surface elevations, and a crimping plate co-operating with the heated surface. 95

10. In a device of the character described, a heated drum, a water marking pressure roll for pressing on the same, having differences in its surface elevations, means for adjusting the pressure thereof, and a crimping 100 plate co-operating with the heated surface.

In testimony that we claim the foregoing we have hereunto set our hands:

JOHN D. TOMPKINS.
FREDERICK H. FULLER.
